EMORY C. DAY, OF LAGUNA BEACH, CALIFORNIA.

SURGICAL SNARE AND UNIVERSAL HANDLE.

Application filed June 20, 1921. Serial No. 478,910.

To all whom it may concern:

Be it known that I, EMORY C. DAY, a citizen of the United States, residing at Laguna Beach, in the county of Orange and State of California, have invented a new and useful Improvement in Surgical Snares and Universal Handles, of which the following is a specification.

This invention has reference to surgical snares and universal handles, and its object is to provide an instrument for the removal of tissues, either natural, such as normal tonsils, or pathological, such as are enlarged or diseased tonsils, and also tumors of various characters.

The invention is of especial value for the removal of enlarged tonsils, and, without limiting the use of the invention to any particular purpose, the following description will be directed to considering the operation of the invention as applied to the removal of enlarged or diseased tonsils.

In accordance with the invention, the usual snare is employed, such, for instance, as a strand of wire or the like looped upon itself and passed through a guide, so that when the loop is drawn more or less into the guide, the diameter of the loop is reduced and is contracted about the part of the tonsil encircled thereby to cause the severing of the portion of the tonsil to be removed quickly and effectively.

The guide is carried by a handle, which may simulate a pistol grip, so that the operator may be enabled to firmly hold the instrument, and carried by the handle is a slide capable of being reciprocated on the handle.

The actuation of the snare is brought about by lever mechanism, either directly or indirectly connected to said slide, and the latter is in turn connected to the snare. The lever-actuating mechanism for the snare is caused to operate in part on the principle of a lever of the third order, such arrangement permitting the holding of the body or handle of the instrument firmly in one position against the wrist-end of the palm of the hand of the operator, while the fingers of the hand may then, with a single squeeze or pull, accomplish the full actuation of the moving part, the contraction of the loop of the snare and the severance of the tonsil.

This invention is an improvement upon the surgical snare shown and described in

my application No. 347,156, filed December 24, 1919.

The invention will be best understood from a consideration of the following detailed description, taken in connection with the accompanying drawings forming part of this specification, with the understanding, however, that the invention is not confined to any strict conformity with the showing of the drawing, but may be changed and modified so long as such changes and modifications mark no material departure from the salient features of the invention as expressed in the appended claims.

In the drawings:—

Fig. 1 is a longitudinal section of the instrument with some parts in elevation;

Fig. 2 is a plan view of the structure shown in Fig. 1;

Fig. 3 is an elevation of the structure of Fig. 1 as viewed from the left hand end of Fig. 1;

Fig. 4 is a section on the line 4—4 of Fig. 1.

Referring to the drawing, there is shown a frame 1, which may be similar in outline to that of a pistol grip. This frame comprises a handhold 2, a top member or stock 3, and a bottom member 4, with the stock and bottom member extending forwardly from the handhold at opposite ends thereof, and with the stock of greater length and forward extension than the bottom member. The stock 3 has a longitudinal slot 3^a defined by two spaced sides 3^b and 3^c.

Pivoted to the forward end of the bottom member by a pivot clamp screw 5, is the lower end of an upstanding lever 6, rising toward and at its upper end entering the stock 3.

Pivoted to the upper rear corner portion of the frame 1, by a pivot stud 7 and a screw 7^a entering the stud, is one end of a manipulating lever 8, shown as of skeleton form for lightness and strength and constituting a lever of the second order, said lever 8 entering at its pivoted end into the slot 3^a in the top member or stock 3.

The lever 6 is an elongated member with a slot 6^a lengthwise thereof and of sufficient width to permit the passage through it of the other lever 8, which second-named lever has a long hand-grip with one portion in the form of a widened slot 9 through which the fingers of the hand may be passed to permit

a firm hold upon the lever 8, and that portion of the lever 8 extending through the slot 6^a in the lever 6, is provided with a curved slot 10, lengthwise of the lever and 5 to one side of the slot 9, the slot 10 increasing in curvature to the end thereof near the pivot screw 7^a.

The lever 6 carries a pin 11 traversing and 10 slidable through the lever and extending through the slot 10, so that the two levers are joined by the pin 11, which is movable with the lever 6 along the slot 10, and travels along and in contact with one edge, (the outer edge), of the slot 10 when in operation, the active edge of the slot being designated by the numeral 12. The pin 11 is carried by the outer end of a flat or leaf spring 13, the inner end of which is mounted on the pivot screw 5, so that the pin 11 because of 20 the yielding of the spring 13, may be readily lifted out of the slot 10 to disengage the two levers, or may be entirely removed from the instrument on the removal of the screw 5.

25 The two-part top member or stock 3 has matching longitudinal grooves 14 on the inner faces of the two parts, and mounted in these grooves, and movable along the slot 3^a between the two parts of the stock, is an 30 elongated block 15, forming a slide. The block or slide 15 has a binding post 16 rising therefrom about midway of its length.

Depending from the block or slide 15, near the rear end thereof, is a slotted tongue 17, 35 in the path of the free end 18 of the upper end of the lever 6, so that said lever has its free end 18 so situated as to engage the tongue 17, and thereby propel the slide 15 toward the handle end of the instrument.

40 At the front end of the stock 3, there is erected a post 19, carrying a screw nipple 20, to which is applied a mutilated screw sleeve 21 of the breech-block type, the screw nipple having similarly arranged mutilated screw- 45 threads, so that the sleeve may be applied to or removed from the nipple by a partial turn. The sleeve 21 is provided with a radial slot 22 for passing a tubular guide 23 through the slot 22 and the sleeve 21, and 50 this guide is for the purpose of carrying a snare wire 24 extending through the guide 23 and post 19 to the binding post 16 to which the snare wire is ultimately secured, after being intermediately formed into a 55 loop 24^a.

Carried by the sleeve 21 is a spring lug 25, capable of engaging in notches or dimples 26, in the adjacent face of the post 19, so that when the parts are assembled and the sleeve 60 21 is turned tightly, the engagement of the spring lug 25, in a notch or dimple 26, prevents the unintentional loosening of the sleeve. The construction just described is a 65 variation of the construction shown in my co-pending application No. 478,909, and

the claims herein addressed to this feature generically cover the other construction.

Secured to the rear edge of the hand-hold 2, is a spur 27, held in a position by a set screw 28, capable of entering any one of a 70 number of threaded sockets 29, so that the spur may be adjusted up and down, or side- 75 wise to constitute an adjustable stop against which the hand grasping the hand-hold 2 may engage.

If it be considered that the slide 15 is pushed forward so that the loop 24^a, in the snare wire 24, is expanded as far as may be necessary for application to a tonsil, or whatever is to be removed, the block 15 participates in such movement along the slot 3 in a straight line, with the ribs 14^a traveling in the grooves 14 in the inside facing walls of the stock. Under these circumstances, the lever 6 of the third class has moved about the 80 pivot 5, with the upper end of the lever approaching the forward end of the stock, and the lever 8 is rocked forwardly for a corresponding distance.

Now, after adjusting the expanded loop 90 24^a of the snare wire about the tonsil to be removed, the lever 8 is drawn toward the hand-hold 2 by the fingers of the operator grasping the finger portion 9 of the lever 8, with the palm of the hand located behind 95 and against the hand-hold. The lever 8 is moved about the pivot stud 7, and at the same time causes movement of the lever 6, because of the connection of the lever 6 to the lever 8 by way of the pin 11 passed 100 through the slot 10. There is, therefore, set up a simultaneous movement of the two levers 6 and 8, constituting a compound lever, with the pin 11 joining them and moving lengthwise of the slot 10 along the curved 105 edge 12 thereof.

The movement of the manipulating lever 8 is toward the operator about the pivot stud 7, and the impulse tending to contract the loop 24^a about the tonsil is in the 110 same direction, that is, toward the operator, and because of the curvature of the slot 12, the force tending to contract the loop is an increasing force corresponding to the increasing resistance met by the loop, where- 115 fore the steadiness of the operation of the instrument is in no wise affected thereby.

The sliding block with its binding post moving in and along the slot 3^a of the stock contributes to the steadiness of the instrument especially in connection with the grooving of the slidable block to allow the flange of the lever 8 to rise higher about its pivot 7 than would occur were the groove absent, the groove in the block 15 being indicated at 120 30.

The guide 23 is removably held in the post 19 so as to make way for accessory surgical instruments when the device is used as a 125 universal handle in place of a surgical snare 130

only. The substitute or accessory surgical instruments may include scissors, forceps, punches, etc.

The device of this invention has the advantage over that of the companion application for the universal handle, in that it has a greater range of movement, and because of the combination of types of levers into a compound lever, constitutes a more powerful structure where power is most needed, as for instance, at the completion of the stroke of the lever action.

What is claimed is:—

1. A frame comprising a handhold, a stock, and a bottom member, with the stock and bottom member extending forwardly from the handhold at the upper and lower ends, an upstanding lever pivoted to the forward end of the bottom member and slotted lengthwise thereof, a manipulating lever pivoted at its upper end to the frame and entering the slot of the first-mentioned lever, said manipulating lever having a curved slot, and a pin passing through the first-mentioned lever and extending through the curved slot of the manipulating lever so as to join the two levers together, and a slide actuated by the movement of the upstanding lever.
2. A surgical snare comprising a body portion having a hand-hold corresponding to a pistol grip with a stock carried by and projecting from the hand-hold, said hand-hold also having a forwardly projecting portion at the end remote from the stock, a slide carried by the stock and guided therealong, an upstanding lever pivoted at one end to the forward end of the lower projection of the hand-hold and at the upper end engaging the slide to propel it, and slotted lengthwise thereof and another lever pivoted at the upper end to the rear portion of the stock and entering the slot of the upstanding lever and engaging the said lever between its ends whereby the two levers constitute a compound lever for actuating the slide and the latter having means for the attachment of surgical devices thereto.
3. A surgical snare comprising a body portion including a hand-hold with a forwardly projecting lower end, a stock fast at the rear end to the upper end of the handhold and also projecting forwardly, said stock having spaced side members with matching grooves on the facing portion, a slide mounted in the stock and guided by the groove to move therealong, and a compound lever with one element pivoted to the forward end of the lower projection of the handhold and rising into engaging relation to the slide and the other element being pivoted to the rear end of and depending from the stock and the two elements of the compound lever being connected by a sliding pivot, and a second-named element of the
4. A surgical snare comprising a body portion including a hand-hold with a forwardly projecting lower end, a stock fast at the rear end to the upper end of the handhold and also projecting forwardly, said stock having spaced side members with matching grooves on the facing portion, a slide mounted in the stock and guided by the groove to move therealong, and a compound lever with one element pivoted to the forward end of the lower projection of the handhold and rising into engaging relation to the slide and the other element being pivoted to the rear end of and depending from the stock and the two elements of the compound lever being connected by a sliding pivot, and a second-named element of the compound lever having finger-holds, whereby the hand of the operator may grasp the hand-hold in the palm of the hand with the fingers engaging the finger-hold of the second-named element of the compound lever to move the block with increasing force toward the palm of the hand of the operator.
5. In a surgical snare or like instrument, a body member, comprising a hand-hold simulating a pistol grip with a lower forward extension and a stock at the upper end of the hand-hold extending forwardly to a greater extent than the hand-hold, said stock having a longitudinal slot therethrough with guiding grooves on opposite sides, a slide mounted in and movable longitudinally of the slot and held therein by the grooves, a lever structure comprising two elements, one pivoted in the stock near the rear end and the other pivoted to the forward extension of the hand-hold and the two elements having a sliding pivoted connection intermediate of their lengths and the compound lever being connected to the slide to actuate it by the hand of an operator grasping the hand-hold and one member of the compound lever, and means whereby the levers and parts with which they coact are retained removably on the body member.
6. A surgical snare, comprising a suitable handle provided with a stock, a screw nipple at the forward end of the stock, a mutilated screw sleeve for rapid release thereof from

the stock and provided with a radial slot, a tubular guide for lateral introduction into the slot, a spring lug radial to the sleeve, and a post at the outer end of the stock and having notches to receive and temporarily lock the spring lug.

7. A surgical snare comprising a suitable handle provided with a stock, a screw nipple on the stock having mutilated screw threads, a mutilated screw sleeve applied to or removed from the nipple by a partial turn, said sleeve having a radial slot, a tubular guide carrying the snare wire, said guide adapted to be passed through the slot, and means whereby when the sleeve is turned tightly on the nipple the accidental loosening of the sleeve is prevented.

8. In a surgical instrument, a fixed part having mutilated screw threads, a movable part having mutilated screw threads to engage the threads of the fixed part, so it may be applied to or removed from the fixed part by a partial turn, the movable part having a radial slot, a guide of a size to be passed into the slot and held by the movable part, a spring lug carried by the movable part and depending therefrom, and notches to be engaged by the lug to prevent the accidental loosening of the movable part.

In testimony that I claim the foregoing as my own, I have hereto affixed my signature.

EMORY C. DAY.
